UNITED STATES PATENT OFFICE.

THEODORE H. SKINNER, OF ONEIDA, NEW YORK, ASSIGNOR TO ONEIDA COMMUNITY, LIMITED, OF ONEIDA, NEW YORK, A CORPORATION OF NEW YORK.

REINFORCED CONCRETE STRUCTURE.

1,008,210.

Specification of Letters Patent. Patented Nov. 7, 1911.

Application filed April 19, 1909. Serial No. 490,850.

To all whom it may concern:

Be it known that I, THEODORE H. SKINNER, of Oneida, in the county of Madison, in the State of New York, have invented 5 new and useful Improvements in Reinforced Concrete Structures, of which the following, taken in connection with the accompanying drawings, is a full, clear, and exact description.

10 This invention relates to certain improvements in reinforced concrete structure as applied more particularly to concrete floors and beams at their junctions with concrete columns.

15 The main object is to establish a cantaliver reinforcement in the concrete column and floor at their junctions one with the other, by embedding portions of the reinforcing members in the column above and 20 beneath the plane of the floor and similarly embedding other portions of the same reinforcing members in the floor or beam some distance beyond the vertical plane of the column during progressive building, so that 25 when the concrete is set to firmly retain the reinforcing members in place, such members not only serve to resist shearing and tensile strains upon the floor, but also serve to centralize such strains upon the column where 30 the pressure resistance is greatest, and to counteract the bending strains on the floor at opposite sides of the column.

Another object is to unite the ends of the lower and upper cantaliver members or rods 35 so as to transmit the bending strains upon the floor and arms of the cantaliver reinforcement to the portion of the column above, as well as to that portion below, the plane of the floor.

40 A further object is to rigidly connect the column portions of the cantaliver reinforcing members so as to afford additional resistance to bending or deflection of the cantaliver arms, and at the same time establishing unity and symmetry in the reinforcement.

In other words, the invention, briefly stated, consists in producing a unitary self-sustaining cantaliver reinforcement of the

open-work skeleton type, which is at once 50 light, strong and durable and capable of sustaining large floor areas and concentrating the strains from such areas directly to and axially of the column.

Other objects and uses relating to specific 55 parts of the invention will be brought out in the following description.

In the drawings—Figure 1 is a top plan of a portion of a concrete floor and two columns showing two of my improved cantaliver reinforcements embedded therein, one for each column. Fig. 2 is a vertical sectional view through a portion of the floor and adjacent portions of the columns except that the attaching members for the reinforcing arms and center supporting rod are shown in the elevation. Figs. 3 and 4 are top plan views of modified forms of attaching members. Figs. 5 and 6 are sectional views taken respectively on lines 70 5—5, Fig. 3, and 6—6, Fig. 4.

In Figs. 1 and 2 I have shown a considerable section of a concrete floor —1— as supported upon a plurality of, in this instance, two concrete columns —2— which are spaced 75 some distance apart to indicate the relative positions of the cantaliver reinforcements which are embedded in the columns and floor, one for each column. Each of these cantaliver reinforcements comprises an upright supporting rod or tubular bar —3—, a series of rings or spiders —4— constituting attaching members mounted upon and adjustable lengthwise of the rod or bar —3—, and a plurality of radially projecting reinforcing members —5— arranged in pairs equidistant apart around the central upright rod or bar —3—, and having their ends connected to the attaching members —4—, the reinforcing members —5— of each pair being arranged diametrically opposite to each other so as to produce a unitary cantaliver structure, with its axis substantially coincident with that of the column. Although it is desirable to arrange 80 85 90 95 these reinforcing arms symmetrically or equidistant from each other around a common axis coincident with that of the column,

it is evident that this arrangement is not absolutely necessary so long as such members are nearly equally distributed around such axis; and in fact in some places, especially 5 in the direction of greatest span, additional reinforcing members —5— may be installed at such side of the axis of the column during progressive building. These attaching members, therefore, constitute an important 10 feature of my invention, and are preferably located within the cross-sectional area of the column and above and beneath the plane of the floor —1—, as clearly shown in Fig. 2.

Each attaching member preferably 15 consists of a central apertured hub and a series of radial arms spaced equidistant apart and corresponding in number to the number of reinforcing members —5— which may be required, said arms being provided with 20 apertures for receiving the upright ends of the reinforcing members —5— to hold the latter a fixed distance apart and prevent their relative radial movement during progressive building of the concrete.

25 In some instances the outer ends of the arms of the attaching members —4— may be tied together by a circular band, as shown in Fig. 3, but in all cases the arms are spaced apart to permit the concrete to be worked 30 through and around all parts of the attaching members and adjacent reinforcing members so as to firmly embed the entire cantaliver structure in the concrete.

For light or moderate loads each of the 35 reinforcing members —5— may consist of a continuous wire or metal rod or bar having its intermediate portion deflected laterally or horizontally a considerable distance forming V-shape reinforcing arms and its 40 ends extended vertically in opposite directions through alined apertures in the arms of the attaching members —4— so as to hold the V-shape extensions —5— a fixed distance apart circumferentially and laterally. These arms are preferably intersected 45 by a series of concentric rings —6— of wire or similar comparatively light metal and are usually tied at their intersections to said rings by any suitable fastening means, as 50 tie wires —7—, which, in this instance, are extended diagonally back and forth across the V-shape extensions or reinforcing members —5— thereby forming braces or truss members —8— which prevent in a measure 55 compression or distention of the opposite sides of the V-shape extensions —5—.

The attaching members —4— which are 60 adjustable vertically along the rod or bar —3— during progressive building to conform to the position at which it is desired to locate the cantaliver reinforcements, are held in their adjusted position by suitable

fastening means, as set screws —9—, Figs. 5 and 6.

The upright rods or bars —3— are positioned in the building where it is desired to erect the column, and are extended from floor to floor as the building progresses; the attaching members —4— being previously placed upon the upright rod, and, together 70 with the reinforcing arms —5— are adjusted and secured in their adjusted positions during such progressive building, the forms, not shown, being secured in proper position to receive the concrete for the columns and floor in which the reinforcing elements become embedded. During this progressive building the retaining members, such as the attaching members —4—, together with the rings —6— serve to retain 80 the reinforcing arms —5—, and parts secured thereto, in fixed relation to each other.

The portions of the arms —5— adjacent to the innermost attaching members —4— are deflected rather abruptly, thereby preventing relative endwise movement of said arms in the attaching members. In placing these reinforcing arm —5— in position, the attaching members —4— below the floor are first secured in place, after which the downwardly projecting ends of the arms —5— are inserted in their corresponding apertures in their attaching members, leaving the upwardly projecting ends of said arms free to receive the attaching members above the 95 floor, the latter members being then secured in proper position and tightened to hold the arms a fixed distance apart circumferentially, and also to hold said arms against endwise movement. The rings —6— may be 100 secured to the arms —5— either before or after the latter are placed in position in the building, but it is evident that before these rings are permanently tied to the arms, the latter may be rocked or adjusted laterally 105 in the attaching members —4— so as to position them the desired distance apart according to the requirements of the work under way.

It may be understood from the foregoing 110 description and the drawings that the attaching members of the cantaliver arms may be firmly connected together and positioned on the central rod —3— as a unit instead of positioning the separate parts independently, and when so assembled has the additional advantage that it may be allowed 115 to settle with the concrete in which it is to be embedded during progressive building.

What I claim is—

1. A cantaliver reinforcement for concrete columns and floors comprising an upright column reinforcing bar extending through and above the plane of the floor, at

taching members mounted on the bar above and below the plane of the floor, and rods connecting said members and, having their intermediate portions deflected laterally beyond the column and into the plane of the floor, said attaching members and rods being embedded in the floor and column during progressive building.

2. A cantaliver reinforcement for concrete columns and floors comprising attaching members and means for supporting them in planes above and below the plane of the floor in combination with rods having their ends attached to said members and their intermediate portions extended laterally beyond the column into the plane of the floor, said members and rods being embedded in concrete during progressive building.

3. A cantaliver reinforcement for concrete columns and floors comprising attaching members arranged one above the other some distance apart above and beneath the plane of the floor, means for holding the members in such position, reinforcing rods having their ends attached to said members and their intermediate portions deflected laterally beyond the column and into the plane of the floor forming floor reinforcing arms, the opposite sides of each arm converging laterally from the column.

4. A cantaliver reinforcement for concrete columns and floors comprising attaching members arranged one above the other some distance apart above and beneath the plane of the floor, means for holding the members in such position, reinforcing rods having their ends attached to said members and their intermediate portions deflected laterally beyond the column and into the plane of the floor forming floor reinforcing arms, the opposite sides of each arm converging laterally from the column, and cross connections between the opposite sides of each arm.

5. A cantaliver reinforcement for concrete columns and floors comprising attaching members arranged one above the other coaxial with the axis of the column in planes above and beneath the plane of the floor, supporting means for said members and floor reinforcing rods having their ends attached to said members and their intermediate portions deflected laterally beyond the column within the plane of the floor forming floor reinforcing arms, and connections between said arms also in the plane of the floor, said attaching members, rods and connections between the arms being embedded in concrete during progressive building.

6. A cantaliver reinforcement for concrete columns and floors comprising attaching members and means for supporting them in

planes one above the other coaxial with the axis of the column above and beneath the plane of the floor, floor reinforcing rods arranged substantially equi-distant apart from said axis and having their ends connected to said members and their intermediate portions deflected laterally beyond the column and within the plane of the floor forming a series of radially projecting floor reinforcing arms.

7. A cantaliver reinforcement for concrete columns and floors comprising attaching members and means for supporting them in planes one above the other coaxial with the axis of the column above and beneath the plane of the floor, floor reinforcing rods arranged substantially equi-distant apart from said axis and having their ends connected to said members and their intermediate portions deflected laterally beyond the column and within the plane of the floor forming a series of radially projecting floor reinforcing arms, and additional floor reinforcing members connecting said arms.

8. A cantaliver reinforcement for concrete columns and floors comprising attaching members and means for supporting them one above the other coaxial with the axis of the column in planes above and beneath the plane of the floor, trussed arms arranged about said axis substantially equi-distant apart and having their ends attached to said members and their intermediate portions projecting laterally from the column within the plane of the floor, said members and arms being embedded in the concrete during progressive building.

9. A cantaliver reinforcement for concrete columns and floors comprising an upright rod coaxial with the axis of the column; attaching members slideable on said rod, and positioned respectively above and beneath the plane of the floor, separate devices for holding said members in their adjusted position, and floor reinforcing arms having their ends attached to said members and their intermediate portions projected laterally some distance beyond the column within the plane of the floor, said upright rod, attaching members and arms being embedded in the concrete during progressive building.

10. A cantaliver reinforcement for concrete columns and floors comprising attaching members arranged one above the other coaxial with the axis of the column in planes above and beneath the plane of the floor, floor reinforcing rods arranged about said axis and having their ends attached to said members, and their intermediate portions deflected laterally beyond the column in outwardly converging lines forming a series of

radial arms within the plane of the floor, and diagonal braces connecting opposite sides of the arms whereby each arm becomes a trussed reinforcement.

5 11. A cantaliver reinforcement for concrete columns and floors comprising an upright column reinforcing rod, attaching members slideable on the rod above and beneath the plane of the floor, means for holding the attaching members in their adjusted

position, and trussed arms having their ends attached to said members, portions of said arms projecting beyond the column within the plane of the floor.

In witness whereof I have hereunto set 15
my hand this 12th day of April 1909.
